ATTORNEY'S

UNITED STATES PATENT OFFICE.

EDWARD G. SCHLEICHER, OF STAMFORD, CONNECTICUT.

VEHICLE-TIRE.

1,289,929.

Specification of Letters Patent. Patented Dec. 31, 1918.

Application filed November 17, 1917. Serial No. 202,467.

To all whom it may concern:

Be it known that I, EDWARD G. SCHLEICHER, a citizen of the United States, residing at Stamford, county of Fairfield, and State 5 of Conn., have invented new and useful Improvements in Vehicle-Tires, of which the following is a specification.

This invention relates to a vehicle tire in which a plurality of flat side by side trans-10 versely arranged members form the wall of an annular tread to permit positive traction and prevent skidding or side slip.

The object of the invention is to arrange on the circumference of a casing a number 15 of tread sections composed of abrading substance and fabric adapted to grip the ground in alternate sequence.

The invention comprehends means for securely clamping the tread sections together 20 in compact annular formation so as to prevent lateral displacement and circumferential creep.

The invention resides in the novel combinations hereinafter described and claimed, 25 and illustrated in the accompanying drawings in which:

Figure 1 represents a transverse section of a tire embodying this invention.

Fig. 2 is a longitudinal section of a por-30 tion of the tire.

Fig. 3 is a side view of an abrading section.

In this drawing the letter *a* designates a casing which as shown is preferably of the 35 clincher type. On the periphery of this casing is mounted a series of sections *b* of tough fabric such as cotton duck. The cotton duck is rendered water-proof by immersing it in a solution of rubber cement. 40 Each section has a convexed top *c* to contact with the ground and a concave inner portion *d* shaped to conform with the periphery of the casing. Each of the sections is provided with two notches *e* one being opposite the 45 other.

Alternate layers of abrading material *f* are arranged between the sections of cotton duck. These layers are of the same contour as the sections *b* and have notches *g* corresponding 50 to the notches in the fabric. Each abrading section consists of a piece of fabric saturated or infused with a fine substance such as sand or other gritty material mixed with an adhesive. The fabric with its gritty sub-

stance adhering to it is water-proofed by 55 a gum or rubber cement as noted above.

The sections of fabric and abrading sub-stance are closely packed together with their flat faces abutting each other. These sec-tions are securely held together by means of 60 a metal band *h* shaped to correspond to the concave inner portions of the sections. The band is equipped with rim portions *i* to embr-ace the lateral portions of the sections. The band can be vulcanized directly to the 65 circumference of the casing to prevent it from shifting or flying off. The ends of the rim are bent inwardly to hook or engage the notches in the sections as indicated in Fig. 1. This method of fastening the sections to-70 gether obviates lateral as well as centrifugal shift of the sections relative to the band.

The diameter of the band is somewhat smaller than the casing so that when the cas-ing is inflated the concavity of the band will 75 frictionally engage the periphery of the cas-ing, thus effectively preventing movement of the band. The casing in practice does not receive its full pressure of air, so that when a part of the casing is compressed by strik-ing an obstruction, the other portion will 80 swell upward by the compression of the air and thereby hug the band. When the tread sections strike a projecting stone or rut in the roadway, the band will move centri-pe-tally and by its transverse rigidness will 85 compress a large area of the casing, thereby absorbing the shocks otherwise sustained by the wheel.

As indicated in the drawing the sections 90 of water-proof fabric and abrading sub-stance are mounted on a pneumatic casing, but it will be readily understood that the sections with slight alterations of the config-uration could be made for a solid tire and 95 directly mounted on to the rim of a wheel.

I claim:

1. A vehicle tire comprising a plurality of flat transversely arranged side by side sections of fabric forming the tread of an 100 annular tire, the alternate sections of which are provided with an abrading substance.

2. A vehicle tire comprising a plurality of flat transversely arranged side by side sec-tions of fabric forming the tread of an annu-lar tire, the alternate sections of which are provided with an abrading substance, and a 105 rim for fastening the sections together.

3. A vehicle tire comprising a plurality of flat transversely arranged side by side sections of fabric having oppositely disposed notches forming the tread of an annular tire, the alternate sections of which are infused with an abrading substance, and a rim having ends to engage the notches.
- 5

In testimony whereof I have hereunto set my hand in the presence of two subscribing witnesses.

EDWARD G. SCHLEICHER.
